UNITED STATES PATENT OFFICE.

CHARLES ARNOIS, OF BROOKLYN, NEW YORK.

MANUFACTURE OF CARBONIC ACID.

SPECIFICATION forming part of Letters Patent No. 368,123, dated August 9, 1887.

Application filed July 15, 1886. Serial No. 208,084. (No model.)

To all whom it may concern:

Be it known that I, CHARLES ARNOIS, a citizen of the United States, residing at Brooklyn, in the county of Kings and State of New York, 5 have invented new and useful Improvements in Process for Manufacturing Carbonic Acid, of which the following is a specification.

This invention relates to an improved process for manufacturing carbonic-acid gas, which 10 process consists in passing a current of water-gas through a heated mass of a metallic oxidizing agent, such as oxide of iron, and then separating the products resulting from the reaction of the oxidizing agent upon the water-gas by condensing the steam, leaving the carbonic acid in a gaseous form ready for use. When the metallic oxidizing agent has become 15 exhausted, the supply of water-gas is stopped and the oxidizing agent is regenerated by passing a current of atmospheric air through it.

The apparatus which may be used in carrying out my invention is illustrated in the accompanying drawing, which represents a longitudinal vertical section.

25 In the drawing, the letter A designates an air-tight receptacle, which I call the "converter," and which is provided with a perforated bottom or grate, a. The space above this bottom is filled with a metallic oxide, such 30 as oxide of iron, oxide of manganese, oxide of copper, or with any of the compounds of said oxides, such as the manganates, permanganates, or chromates, or with a mixture of two or more of the above-named oxidizing agents. 35 I use by preference the oxide of iron or manganese, which I heat up to above 600° Fahrenheit; but the temperature to which the oxidizing agent is heated must be below the melting point of the same. Below the bottom a of the converter 40 are three pipes, b c d, the pipe b being intended for supplying water-gas, the pipe c for supplying steam, and the pipe d for supplying air. From the top of the converter extends a pipe, e, the upper end of which is closed by a valve, 45 f. From the side of the pipe e extends a pipe, g, into a liquid seal, B, and from the top of this liquid seal extends a pipe, h, into a condenser, C, which connects by a pipe, i, with the gas-holder D. When the contents of the 50 converter have been heated up to the desired temperature—which may be accomplished by admitting a supply of water-gas through the

pipe b and at the same time a supply of air through the pipe d and then igniting the water-gas, or which may be accomplished by 55 any other suitable means—I open the stop-cock of the pipe g and pass a current of water-gas through the heated oxidizing agent in the converter. On its passage through the oxidizing agent the water-gas is converted into carbonic 60 acid and steam, and the mixture of carbonic acid and steam thus produced passes through the pipe g into the liquid seal B, and thence through the pipe h into the condenser C, where it is exposed to a shower of cold water. The 65 steam contained in the mixture is thereby condensed, while the gaseous carbonic acid escapes through the pipe i into the holder D.

When the oxidizing agent in the converter A has become to a certain degree exhausted, 70 I close the water-gas supply-pipe b. Then I open the steam-pipe c and blow steam through the converter, whereby the gases contained therein are driven out through the pipe g, and after the gases have been driven out I close 75 the steam-pipe c and open the valve f and the air-pipe d, so as to pass a current of air through the exhausted oxidizing agent in the converter. By the action of the air the oxidizing agent is 80 regenerated, and when this has been accomplished the air-pipe d is closed, the gases contained in the converter are blown out by steam, the valve f closed, and a new supply of water is passed through the converter, as above described.

85 What I claim as new, and desire to secure by Letters Patent, is—

1. The process herein described of manufacturing carbonic-acid gas, which consists in passing water-gas through a heated mass of a metallic oxidizing agent and thereby converting the water-gas into carbonic acid and steam, then condensing the steam to leave the carbonic acid in a gaseous form, and then collecting the carbonic-acid gas in a holder for subsequent use, substantially as set forth.

2. The process herein described of manufacturing carbonic-acid gas, which consists in passing water-gas through a heated mass of metallic oxidizing agent and thereby converting the water-gas into a mixture of carbonic acid and steam, subjecting the said mixture to a shower-bath, leaving the carbonic acid in a gaseous form, and then collecting the car-

bonic-acid gas in a holder for subsequent use, substantially as set forth.

3. The process herein described of manufacturing carbonic-acid gas, which consists in 5 passing water-gas through a heated mass of a metallic oxidizing agent, thereby converting the water-gas into carbonic acid and steam, then condensing the steam, leaving the carbonic acid in a gaseous form, then collecting 10 the carbonic-acid gas in a holder, and finally regenerating the exhausted oxidizing agent by driving off the gases mixed therewith and passing a current of atmospheric air through the exhausted oxidizing agent, substantially as set 15 forth.

4. The method, substantially as described, for regenerating the oxidizing agent after the same has become exhausted, which consists in driving out the gases mixed with the exhausted oxidizing agent and then passing through said exhausted oxidizing agent a current of atmospheric air.

In testimony whereof I have hereunto set my hand and seal in the presence of two subscribing witnesses.

CHARLES ARNOIS. [L. S.]
